US0D1024103S

(12) **United States Design Patent** (10) Patent No.: **US D1,024,103 S**
 Menu et al. (45) Date of Patent: ** Apr. 23, 2024

(54) **DISPLAY SCREEN WITH AUGMENTED REALITY OVERLAY OF A GRAPHICAL USER INTERFACE**

(71) Applicant: **Brainlab AG**, Munich (DE)

(72) Inventors: **Lily Menu**, Munich (DE); **Kilian Brendel**, Munich (DE)

(73) Assignee: **BRAINLAB AG**, Munich (DE)

(**) Term: **15 Years**

(21) Appl. No.: **29/832,635**

(22) Filed: **Mar. 29, 2022**

(30) **Foreign Application Priority Data**

(57) **CLAIM**

The ornamental design for a display screen with an augmented reality overlay of a graphical user interface, as shown and described.

DESCRIPTION

The sole FIGURE is a front view of a display screen with an augmented reality overlay of a graphical user interface showing the new design.

The outer broken-line rectangle shows the perimeter of a display screen and forms no part of the claimed design. All other broken lines showing portions of the graphical user interface depict portions of the article and form no part of the claimed design.

1 Claim, 1 Drawing Sheet
